UNITED STATES PATENT OFFICE.

HUTCHINS C. CADY, OF COLUMBUS, OHIO.

SUPPORTING-BRACKET FOR DISPLAY-CARDS.

SPECIFICATION forming part of Letters Patent No. 669,680, dated March 12, 1901.

Application filed August 25, 1900. Serial No. 27,970. (No model.)

To all whom it may concern:

Be it known that I, HUTCHINS C. CADY, a citizen of the United States, residing at Columbus, in the county of Franklin and State 5 of Ohio, have invented a certain new and useful Improvement in Supporting-Brackets for Display-Cards, of which the following is a specification.

My invention relates to the improvement 10 of supporting brackets or braces for that class of display-cards which are adapted to be supported in an upright or inclined position upon a counter, table, or other horizontal surface, and has particular relation to supports for 15 photographs, calendars, and business and similar display-cards.

The objects of my invention are to provide a simple, convenient, and inexpensive supporting-bracket of this character of an improved construction whereby the same may 20 be readily set up or folded against the card upon which it is used and to produce other improvements, the details of construction of which will be more fully pointed out herein- 25 after. These objects I accomplish in the manner illustrated in the accompanying drawings, in which—

Figure 1 is a view in perspective, showing a card supported by my improved bracket. 30 Fig. 2 is a face view of the standard-section of my improved support, showing the form of the same prior to bending. Fig. 3 is a side elevation of the same. Fig. 4 is a longitudinal section of the same with the lower end folded to form a pocket and with the upper end bent for attachment to the card. Fig. 5 is an end view of the same. Fig. 6 is an under side view of the lower brace-section prior 35 to bending, and Fig. 7 is a side elevation of 40 the same.

Similar numerals refer to similar parts throughout the several views.

In carrying out my invention I form a bracket standard-section consisting of a strip 45 1 of cardboard or similar material, the rear side of the latter being faced with a longitudinal strip of paper or cardboard 2, preferably of less thickness than the portion 1. This backing-strip 2 is of greater length than 50 the strip 1 and has its upwardly-extending portion adapted to be bent or inclined out-

ward, as indicated at 3. The lower end extension of the strip 2 is extended laterally to form a T-head 4. As indicated in the drawings, the upper extension or tongue portion 3 of the backing-strip 2 is adapted to be glued or otherwise firmly secured to an upper point on the back of a display-card 5, while the extension 4 is adapted to be bent upward against the rear side of the lower portion of the section 1, after which its laterally-projecting portions 4^a are bent about the lower portion of the section 1, so as to embrace the same, these lateral extensions being glued or otherwise secured to the outer side of said section 1. 65

In constructing the lower arm or brace of my improved bracket I form the same as prescribed for the upper standard of two strips or sections 6 and 7, the upper strip being longer than the lower strip, resulting in the 70 formation of tongues or strip extensions 6^a and 6^b. This lower brace or arm, which is adapted to be supported in a substantially horizontal position, has its end extension 6^a bent downward and secured to the lower portion 75 of the card 5, while its tongue extension 6^b at its outer end is also adapted to be bent downward and detachably inserted between the portion 4 of the strip 2 and the body of said strip. By this construction it will be 80 seen that the lower reinforced end of the standard-section may bear upon the table or counter top and that said standard-section and lower brace-section of said brackets may be made of such relative lengths and sizes as 85 to permit of the bracing or support of the card 5 at desirable angles. It will also be observed that by removing the tongue 6^b of the strip 6 from the pocket formed by the folding of the portion 4 of the strip 2 the 90 standard-section and brace-section may be readily folded in against the rear side of the card 5, thus admitting of a number of said cards being closely packed.

In forming the standard brace-sections of 95 my improved bracket it will be observed that the construction of each of the same in two sections will insure the desired rigidity and strength thereto.

Having now fully described my invention, 100 what I claim, and desire to secure by Letters Patent, is—

In a supporting-bracket for display-cards, the combination with the united standard strips 1 and 2, the latter having extensions 3 and 4, said extension 4 being in the form of 5 a T-head and bent upward against the body of the standard and its laterally-projecting portions made to embrace said standard, of a brace consisting of united strip-sections 6

and 7, the section 6 having downturned ends and one of said ends adapted to be inserted 10 between the extension 4 of the strip 2 and the body of said strip, substantially as specified.

HUTCHINS C. CADY.

In presence of—

R. G. HESSONG,

A. L. PHELPS.
